CLAIM

The ornamental design for a sprinkler bottle, as shown and described.

DESCRIPTION

FIG. 1 is a perspective view of a sprinkler bottle viewing from an upper side, showing my new design;

FIG. 2 is another perspective view thereof, viewing from a lower side;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view showing the sprinkler bottle. The broken lines illustrate portions of the sprinkler bottle that form no part of the claimed design.

1 Claim, 8 Drawing Sheets
